METHOD OF AND APPARATUS FOR
FILTERING OIL

Ulric B. Bray, Palos Verdes Estates, and John K. Russell, Los Angeles, Calif.

No Drawing. Application May 31, 1941,
Serial No. 396,145

8 Claims. (CL 252—326)

1

Our invention relates to the treatment of hydrocarbon oils such as are employed in the lubricating systems of internal combustion engines, including Diesel engines and gasoline engines employed in passenger vehicles and the like. Certain aspects of the invention herein disclosed but not claimed are claimed in our co-pending application Serial No. 396,144.

Some such lubricating oils employed in Diesel and other engines are compounded so that they are alkaline and/or contain oxidation inhibitors to prevent the accumulation of harmful amounts of acid therein during the effective life of the oil.

Our invention finds particular utility in the filtering and purifying of such compounded oil in the lubricating system of an internal combustion engine, and without limiting our invention to this use the application of our invention relates to a lubricating system of an internal combustion engine containing such a compounded oil, which will be hereinafter described to illustrate its features and advantages. Likewise, lubricating oils, whether so compounded or not, commonly contain a detergent carried with the oil through the oil circulating system of the engine during the operation of the engine and acting to remove from the bearing surfaces, piston rings, and cylinder and piston walls and to cause to be carried away from such lubricated parts impurities, which otherwise would accumulate thereon increasing friction and diminishing the efficiency of the engine, and, to illustrate the advantages of our invention, we choose to describe its application to a compounded oil containing such a detergent.

When a lubricating oil is used in an internal combustion engine, it travels in a circulating system which includes the parts or surfaces to be lubricated, comprising the bearing surfaces, the piston rings, and the piston and cylinder walls. During its travel through such a circulating system, the lubricating oil becomes contaminated with impurities, some of which are of such particle size as to be readily removed by the passage of the oil containing them through a conventional filter employing as a straining medium cotton waste or the like. Others of these impurities are so finely divided as to remain suspended in the oil during its passage through such a conventional filter, and it is with such suspended impurities that our invention is principally concerned.

Such suspended impurities include particles of soot, caused by the combustion of the fuel, which accumulate in the oil and deposit upon the bearing

surfaces, piston rings, and piston and cylinder walls, forming with various impurities accumulating in the oil from the breakdown of the oil a hard varnish-like deposit diminishing the clearance between moving parts and causing the piston rings to stick and friction within the engine to be greatly increased. Such suspended impurities include also suspended and colloidal carbon accumulating in the oil from the breakdown of the oil and also fine particles of silica, dust, and other abrasives from the air.

It is known that the detergents commonly employed in lubricating oil in the circulating systems of internal combustion engines have the property of removing such suspended impurities from the bearing surfaces, piston rings, cylinder and piston walls, and surfaces with which the oil bearing the detergent contacts, thus preventing their accumulation upon such surfaces, and by the term "suspended impurities" is meant all such impurities, the accumulation of which upon such surfaces is prevented by a detergent carried by the lubricating oil.

Detergents known to possess such properties include calcium phenylstearate, calcium dichlorostearate, calcium soaps of oxidized petroleum acids such as calcium Alox, calcium salts of phenolic bodies, and calcium salts of alkylated phosphoric acid. By the term "detergent" is meant those substances which may be carried by the oil in the circulating system of an internal combustion engine and which possess a property for removing impurities from and preventing their accumulation upon surfaces with which the oil bearing such material comes in contact, like that property possessed by those materials specifically identified.

We have found that, when there is employed in the oil circulating system of an internal combustion engine containing oil carrying such a detergent a filter or straining device of conventional construction, the detergent exerts its property of preventing the accumulation of impurities in and washing impurities from the filtering or straining medium of the filter device as well as the engine surfaces with which it comes in contact, with the result that the efficiency of the filter is impaired, the accumulation of such impurities in the oil stream is rapid, the detergent in the oil is rapidly consumed, and the life of the oil between drains of the system is relatively short.

An object of our invention is to prevent the removal by the detergent in the oil from the filter or straining device in the oil circulating

system of an engine of impurities deposited therein and to cause the deposition in such a filter or straining device of the suspended impurities in the oil stream. More specifically, it is an object of our invention to remove and entrap in a filtering device in the oil circulating system of an engine suspended impurities at substantially the rate at which they are formed in the oil stream.

As the detergent carried by the oil in the circulating system in an engine removes the impurities from the surfaces upon which they are deposited, the detergent in the oil becomes exhausted, and the capacity of the oil for washing and cleansing such surfaces steadily decreases. It is possible that this fact is due to the formation by the detergent in the oil stream of an envelope around each particle of the suspended impurities, which causes its separation from the surface upon which it has been deposited and its transportation in the oil stream away from such surfaces, so that the detergent from such envelopes is consumed or rendered ineffective, and the cleaning property of the oil is decreased.

It is an object of our invention to remove from oil bearing a detergent in the oil circulating system of an engine suspended impurities taken from the surfaces contacted by the oil stream by the action of the detergent without removing from the oil stream the detergent and while retaining substantially constant the concentration of the detergent in the oil stream.

This object we accomplish by placing within the oil circulating system of an engine a supply of a material capable of agglomerating the particles of suspended impurities removed from the bearing surfaces by the action of the detergent in the oil until the oil is conditioned for filtration or straining. By "conditioning" the oil for filtration or straining, we mean agglomerating particles, themselves of such small size as to pass with the oil through the filtering medium in the presence of the detergent, into such a size or mass as to permit the filtering or straining medium to entrap and retain them.

Since such an agglomerating material is consumed in performing such action, it is an object of our invention to provide in the oil circulating system of an engine a supply of an agglomerating material, the solubility of which is small enough that a supply of practical dimensions will, without exhaustion during the entire period between oil drains, provide a concentration of the material in solution in the oil insufficient to exert a harmful effect upon the engine parts or the cleansing function of the detergent, and the solubility of which is great enough to maintain the concentration of the material in solution in the oil at that value sufficient to agglomerate and thus cause the removal of the suspended impurities at substantially the rate at which they are formed.

If the agglomerating material functions only while the oil bearing the suspended impurities is present in the filtering medium, it will be seen that the time within which the agglomerating action must take place is extremely small as compared with the time required for the oil to circulate through the engine and circulating system, and hence the surface area of the agglomerating material available for contact with the suspended impurities, being all within the filtering medium, controls the dimensions of the filtering medium and requires frequently for effective agglomeration a filtering medium of very

substantial size. One of the objects of our invention is to agglomerate the suspended impurities with a material having a limited solubility in the oil which exerts its agglomerating action 5 simultaneously upon all of the oil in the oil circulating system in the engine as well as in the filter, thus reducing the surface area of the agglomerating material required in the filtering medium and consequently reducing the dimensions of the filtering medium required for effective agglomeration.

Further, it is an object of our invention to condition the oil for filtration or straining to a substantial degree while the oil is in the engine 15 and circulating system outside of the filtering medium connected thereto, so that, when the oil enters the filtering medium, a substantial proportion of it is immediately capable of filtration to remove the agglomerated suspended impurities.

We have found that soaps of alkylolamines such as triethanolamine and tri-isopropanolamine are admirably suited for use as such agglomerating materials. The soaps of alkylamines or arylamines which are sufficiently alkaline to form a soap with an organic acid can be employed. While any alkylolamine may be employed, we prefer to employ a soap of triethanolamine. The triethanolamine is mixed with a fatty acid having the formula

in which x is more than ten, for example, coconut oil fatty acid or hydroxylated fatty acids, for 35 example, castor oil fatty acid, forming a neutral soap so that the mixture does not react alkaline to phenolphthalein.

Such soaps, of which the foregoing are examples and which may be described as agglomerating soaps of limited solubility, may then be heated to liquefaction and sprayed or sprinkled upon a carrier or supporting medium. Such a supporting medium may be in the form of a fibrous material, such as wool, cotton waste, pounded paper, 45 or paper pulp, or in the form of porous particles, such as pressed or ground walnut hulls, ground coconut shells, sawdust, or the like, or substantially nonporous particles, such as quartz or sand particles or the like. We prefer to utilize as a 50 supporting medium a material capable of exerting a filtering or straining action accomplishing the removal of solid impurities and the agglomerated suspended impurities in the oil stream during its passage therethrough.

We have found cotton waste admirably suited for this purpose. The quantity of cotton waste to be employed is determined by the quantity of impurities which it is desired to remove from the oil circulating system before replacement of the filter unit. If it is desired to replace the filtering 60 or straining medium of the filter unit on each occasion when the oil is drained, we have found, for example, that approximately 500 grams of cotton waste will provide the desired filtering action for the required length of time in the circulating system of a small size Diesel engine used upon a tractor for drawing a ground working implement, where the oil is subjected to a high rate of contamination by dust particles and the like.

Likewise, the quantity of agglomerated soap of limited solubility placed on the supporting medium is determined by the quantity of suspended particles which the filtering medium is required 75 to remove between renewals of the filtering me-

dium. This quantity varies with the condition of the engine and the conditions of use. If the engine in the above example be fairly free of deposits on the bearing surfaces caused by the suspended impurities, such a soap to the amount of 0.1 to 0.2 of one percent by weight of the weight of the oil in the crank case charge is sufficient.

The agglomerating soap of limited solubility is distributed substantially uniformly upon the supporting medium.

To follow the illustration herein adopted, the cotton waste so coated or impregnated with the agglomerating soap of limited solubility, for example, a coconut oil fatty acid soap of triethanolamine, is compressed in a container placed in the oil circulating system of the engine, the compression being to such a degree that the fibres of the cotton waste are in such proximity to each other as to effectively entrap and retain solid impurities in the oil stream and the agglomerated bodies of suspended particles carried thereto by the oil stream.

A very small portion of the agglomerating soap immediately passes into solution in the oil stream, travelling with it and the detergent carried by the stream through the system and adjacent the bearing surfaces. The detergent, loosening from the bearing surfaces particles of the character of the suspended impurities and, we believe, forming an envelope around each such particle, carries them to the filter unit where they enter the cotton waste. Also carried by the oil stream to the cotton waste are the solid impurities which are entrapped and retained therein. The suspended impurities, contacting in the cotton waste the agglomerating soap, either in solution in the oil stream or supported upon the cotton waste, are caused to agglomerate or accumulate until they form bodies of sufficient size to be entrapped and retained by the cotton waste. This agglomeration or accretion of the suspended particles is accompanied by a consumption of the agglomerating material of limited solubility, and, as this agglomerating material in solution in the oil stream is thus consumed, it is replaced by the entry into solution in the oil stream of some of the agglomerating material supported upon the cotton waste, so that the concentration of the agglomerating material in solution in the oil stream remains substantially constant.

This agglomeration, entrapment, and retention of the suspended particles in the filter unit is not accompanied by any substantial decrease in the concentration of the detergent in the oil, the presence and consumption of the agglomerating material of limited solubility apparently preventing such a decrease. It is our belief that the suspended particles in their envelopes of the detergent are caused to agglomerate by the triethanolamine soap, and in such agglomeration the detergent is freed from the particles and returned to the oil stream free of them, so that it may repeat its cleansing or washing action, accomplishing the removal of deposited impurities of the character of the suspended impurities from the bearing surfaces in the system.

A limited amount of the agglomerating soap, being dissolved in the oil stream, exerts its effect throughout all of the oil in the circulating system during all of the time that the oil is circulating therethrough, with the result that between the time the colloidal impurities are created in the oil system by use in the engine or washed from the bearing surfaces by the detergent and the time

they enter the cotton waste in the filter unit, a substantial portion of these contaminants are agglomerated to bodies of a size permitting their entrapment and retention by the first fibres of cotton waste in the filter unit contacted by the oil stream. Thus the oil prior to its entry into the filter unit and medium is conditioned to a substantial degree for immediate filtration or straining thereof of suspended impurities. Further conditioning occurs as the oil continues its passage through the filter unit, contacting agglomerating soap supported upon the cotton waste, so that the filtration or straining of the agglomerated bodies of suspended impurities occurs throughout the entire filtering mass.

Triethanolamine alone may be placed upon the cotton waste in the filter unit and will there exert some agglomerating action, but, since triethanolamine has a very much lesser solubility in oil than the agglomerating soaps described herein, the conditioning of the oil in the engine and circulating system prior to its entry into the filtering unit will not be accomplished to any appreciable degree, and, therefore, the portions of the cotton waste first contacted by the oil stream will not operate to entrap and retain agglomerated bodies of suspended particles, and all of such filtration is necessarily performed by the portions of the cotton waste later contacted by the oil stream within the unit.

Furthermore, since the solubility of triethanolamine is so much less in the oil than the agglomerating soaps described herein, the detergents are not freed by the triethanolamine to any appreciable extent from the suspended particles in the oil stream in the engine and circulating system as is the case when the agglomerating soaps described are employed. While the absolute solubilities in oil of triethanolamine and the agglomerating soaps herein contemplated are difficult of determination, being of the order of a few thousandths of one per cent, their relative solubilities in oil are more readily determined, and we have found that the agglomerating soaps of the character herein referred to are in general three or more times as soluble as triethanolamine.

The very substantial increase in volume of the soap made with triethanolamine over the triethanolamine employed permits the distribution of the triethanolamine soap much more uniformly and easily over the entire bulk of the cotton waste or other filtering medium, thus insuring a uniformity of the agglomerating action throughout the entire body of cotton waste and a uniform filtering action throughout the waste, and hence a maximum filtering life for the waste.

As previously pointed out, our invention is of particular utility in connection with the oil circulating systems of Diesel engines employing a compounded oil containing alkaline-maintaining or oxidation-inhibiting materials and a detergent.

As will be seen from the foregoing, our invention contemplates the cleansing from the bearing surfaces of deposited impurities and the agglomeration of such removed impurities and suspended impurities to bodies of sufficient size to be filtered from the oil stream at substantially the rate at which they are formed therein, the accomplishment of such removal, agglomeration, and filtration without substantial diminution of the detergent or cleansing agent in the oil stream, the simultaneous removal of such impurities from the bearing surfaces and agglomeration of the removed and suspended impurities in the oil in the circulating system of the engine preparatory to

the step of filtering the agglomerated bodies from the oil in the system and the maintenance of the rate of agglomeration at the desired substantially constant value between drains of the oil circulating system.

While the foregoing examples of materials are sufficiently capable of performing the objects and providing the advantages of the method and filter of our invention, and while the application of our invention to the oils and engines hereinbefore referred to are illustrative of the oils and engines with which our invention may be advantageously employed, we wish our invention to be understood to be not restricted to the materials hereinbefore specified or to use with the oils and engines hereinbefore referred to for illustrative purposes, but as including all of the materials and for the uses coming within the scope of the claims which follow.

We claim as our invention:

1. The method of treating a flowing stream of substantially non-acidic lubricating oil during contamination by suspended impurities of a particle size insufficient for filtration, which includes the steps of: agglomerating such impurities along the oil stream at substantially the rate at which they are suspended in the oil to bodies of dimensions sufficient for removal by filtration with an agglomerating amino soap of castor oil fatty acids and having slight solubility in the oil; separating said agglomerated bodies from the lubricating oil at substantially the rate at which such bodies are formed by passing the oil containing such bodies through a filter interposed in the stream; and maintaining the quantity of the agglomerating soap in solution in the oil substantially constant by replenishing the soap in solution in the oil at the rate it is removed therefrom by the agglomeration of such suspended impurities.

2. The method of treating a flowing stream of substantially non-acidic lubricating oil containing a detergent during contamination by colloidal impurities, which includes the steps of: conditioning the oil for filtration by agglomerating the colloidal impurities suspended in the oil along the stream with a castor oil fatty acid soap of triethanolamine; filtering said agglomerated bodies from the oil; and maintaining the concentration of said soap in solution in the oil substantially constant at a value preventing the accumulation of colloidal impurities in the oil by replenishing the soap in solution in the oil, simultaneously with the filtration of the oil, at the rate it is removed from the oil by the agglomeration of the colloidal impurities.

3. A filter adapted for treating an oil during contamination by particles of solid impurities and colloidal impurities of smaller size than said particles, comprising: a filter mass of such porosity as to allow the oil and colloidal impurities to pass therethrough and to filter the solid particles therefrom; and an agglomerating amino soap of hydroxylated fatty acid and having slight solubility in oil, the soap being carried by said filter mass in a quantity sufficient to agglomerate said colloidal impurities to bodies of dimensions filtered from the oil by said filter mass at substantially the rate of contamination of the oil by said colloidal impurities during the effective life of said filter mass.

4. A filter adapted for treating an oil during contamination by particles of solid impurities and colloidal impurities of smaller size than said particles, comprising: a filter mass of such porosity as to allow the oil and colloidal impurities to pass therethrough and to filter the solid particles therefrom; and an agglomerating castor oil soap of triethanolamine carried by said filter mass in a quantity sufficient to agglomerate said colloidal impurities to bodies of dimensions filtered from the oil by said filter mass at substantially the rate of contamination of the oil by said colloidal impurities during the effective life of said filter mass.
5. A filter adapted for treating an oil during contamination by particles of solid impurities and colloidal impurities of smaller size than said particles, comprising: a filter mass of such porosity as to allow the oil and colloidal impurities to pass therethrough and to filter the solid particles therefrom; and an agglomerating hydroxylated fatty acid soap of an alkylolamine carried by said filter mass in a quantity sufficient to agglomerate said colloidal impurities to bodies of dimensions filtered from the oil by said filter mass at substantially the rate of contamination of the oil by said colloidal impurities during the effective life of said filter mass.
- 20 6. A process for treating mineral lubricating oil as it is used, said oil containing a detergent material, the process comprising: circulating said used oil; dissolving in said oil a slightly oil-soluble agglomerating amino soap of castor oil fatty acids, said soap being capable of agglomerating to filterable particle size colloidal impurities formed in said oil during use; and passing said oil and contained agglomerated particles through filtering means capable of removing said agglomerated particles and incapable of removing substantial proportions of said detergent.
- 25 7. A filter as in claim 3 wherein the soap is an amino soap of castor oil fatty acids.
8. A filter as in claim 3 wherein the soap is an alkylolamine soap of castor oil fatty acids.
